TELESCOPING LADDER

Filed Sept. 28, 1927

UNITED STATES PATENT OFFICE

RALPH OTTO CLARK, OF ESTHERVILLE, IOWA

TELESCOPING LADDER

Application filed September 28, 1927. Serial No. 222,490.

This invention relates to telescoping ladders, and one object is to provide a ladder the parts of which are formed of pressed sheet metal and having two sections adapted to telescope one within the other.

Another object is to provide such ladder with the telescoping sections thereof so connected by pulleys and cables operated by a crank, that the said sections may be readily 10 and handily expanded for use or telescoped together, as desired.

In the drawing

Figure 1 is a side elevation of the ladder, shown as leaning against a supporting structure;

Figure 2 is a relatively enlarged front elevation of portions of the telescoping ladder sections, taken at their point of connection; 15 Figure 3 is a transverse section on the line 3—3 of Figure 2;

Figure 4 is a vertical, longitudinal section taken through portions of the two telescoping side rails of the ladder sections at their juncture;

Figure 5 is a detail of one of the ladder steps showing the formation of same from sheet metal, the right hand end fold being omitted so as to reveal clearly the method of folding the sheet metal.

In carrying out this invention, I provide a lower ladder section A and an upper section B. These sections are both formed of lengths 25 of sheet metal bent and formed and folded upon longitudinal lines of flexure into the shapes shown, and with the upper section B adapted to telescope within the lower section A. For this purpose the sheet metal strip of each lower side rail C is flexed into a hollow and open tubular structure, rectangular in 30 cross section, having the outer side wall 1, the inner side wall 2, the front and rear walls 3 and 4, the spaced transverse inner front wall 5 and partition 6 adjacent the front wall 3, the inner longitudinal side opening or parting 7 adjacent the rear wall 4, and the marginal flanges 8 at the opening 7. The sheet metal strip of the upper side rail D is flexed into a 35 hollow structure, rectangular in cross section, having the side wall 9, the front and rear walls 10 and 11, the inner side walls 12 meet-

ing centrally at 13 and the spaced transverse webs 14. This rectangular structure represented as a whole at D is adapted to telescope within the structure of the lower rail C formed by the side wall 1, the front and rear 55 walls 4 and 5 and the flanges 8. The side rails C and D of the sections A and B are connected by steps E. These steps are likewise formed of strips of sheet metal each cut and flexed to form the tread face 15, the inset perpendicular webs 16, the end folds 17 with the projecting flanges 18 pierced with rivet holes 19 for attachment to the side rails as shown at 20, and the lower flanges 21 extending perpendicular to the webs 16.

As stated, the upper section B is telescoped 60 within the lower section A, and the upper end of the lower section A is reinforced with a number of cross braces 22 which are likewise riveted to the side rails C, as 65 shown at 23. Pulley shafts 24, 25 are journaled transversely near the lower and upper ends of the lower section A, between the webs 5 and 6, the said shafts having bearings 70 through the walls 1 and 2. Pulleys 26, 27 are rigidly mounted upon the ends of the shafts 24, 25, within the side rails C, long slots 28 being cut through the webs 5 and 6 to accommodate said pulleys and cables 29. The cables 29 are attached at one end to the 75 lower pulleys 26, and after being wound around said pulleys the requisite number of times, are passed up over the upper pulleys 27 and through the slots 28 and have their ends secured at 30 to the lower ends of the 80 upper rails D. A ratchet wheel 31 is rigidly mounted on an end of the lower shaft 24 extended through one of the rails C, and a pawl 32 pivoted on the said rail C, as at 33, controls the ratchets 31 on rotation of the shaft 24 to 85 wind the cables 29 upon the pulleys 26; but of course by releasing the said pawl the said cables may be allowed to unwind from the 90 said pulleys. A hand crank 34 at the extended end of the lower shaft 24, affords means 95 for turning the lower shaft 24 and so operating the mechanism of the ladder.

In use the upper section B may be readily 100 extended by rotating the crank 34, or may be telescoped back into the lower section A by

releasing the pawl 32. This structure therefore affords a very light and strong as well as convenient telescoping ladder.

It will be noted that in the process of telescoping the upper section into the lower section, the ends of the steps E of the upper section traverse the inner side openings 7 of the rails C of the lower section.

While I have here described a preferred form of construction, it is understood that the structural details may be varied, within the scope of the appended claims.

I claim:

1. An extensible ladder as described, comprising a lower section and an upper section adapted to be slidably telescoped in and extended from the lower section, means slidably engaging said upper section in telescoped relation with said lower section, said lower section having side rails each including a longitudinally extending box-like housing, and operative means for extending said upper section from said lower section, said operative means being positioned interiorly said housing.

2. An extensible ladder as described, comprising a lower section and an upper section adapted to slidably engage the lower section, said upper section comprising a single sheet of metal formed and folded upon longitudinal lines of flexure to form a channel shaped member, the terminal portions of the flanges thereof being returned upon themselves to form opposed box-like members, the lower section comprising a single sheet of metal formed and folded upon longitudinal lines of flexure to form a channel shaped member slidably embracing the upper section, one of the flanges being flexed upon itself to form a box-like housing and further returned upon itself to form a partition interiorly said box-like housing, and operative means for extending said upper section from said lower section, said operative means being mounted on said partition interiorly said housing.

3. In a device of the kind described, a side rail of a ladder formed of a single sheet of metal formed and folded upon longitudinal lines of flexure to form a partition, a box girder formed around said partition and interiorly partitioned thereby, the terminal portion of the sheet being extended from the box-girder and bent right angularly to form a wall parallel with and spaced from said girder.

4. In a device of the kind described, a side rail of a ladder formed of a single sheet of metal formed and folded upon longitudinal lines of flexure to form a partition, inner and outer front walls spaced from opposite sides of the partition and connected together therearound to form a box-like housing, the sheet of metal being extended laterally from the outer front wall and formed with a right angularly extending rear wall parallel with

and spaced from the inner front wall and having a flange extending towards said inner front wall, said inner front wall being also flexed upon itself to form a flange aligned with and extending towards said first mentioned flange.

5. In a ladder of the kind described, a side rail formed of a single piece of metal having one of its longitudinal side portions longitudinally flexed upon itself to form a box-like structure, the side terminal portion being further longitudinally flexed upon itself to form a longitudinally extending web disposed transversely interiorly said box-like structure, and the other side portion of the piece of metal being longitudinally flexed to form a longitudinally extending wall oppositely said box-like structure, the side terminal portion of said second mentioned side portion being further turned right angularly towards said box-like structure, the edge of said second mentioned terminal portion being spaced from said box-like structure.

6. In a ladder of the kind described, a side rail formed of a single sheet of metal formed and folded upon longitudinal lines of flexure so as to form an outer side wall, and front and rear walls flexed right-angularly to the side wall, the front wall being further flexed right-angularly in parallelism with the side wall to form an inner side wall, said inner side wall being further flexed upon itself to form a flange parallel to the inner side wall, the terminal portion of said flange being further flexed to form an inner front wall parallel with the first mentioned front wall, said inner front wall being flexed parallel with and engaging said first mentioned side wall and further flexed right-angularly thereto to engage said inner side wall.

In testimony whereof I affix my signature.

RALPH OTTO CLARK.
